MANUFACTURE OF AROMATIC HYDROCARBONS FROM PETROLEUM OIL

Filed Dec. 8, 1936

UNITED STATES PATENT OFFICE

2,207,552

MANUFACTURE OF AROMATIC HYDRO-CARBONS FROM PETROLEUM OIL

James W. Putt, Beverly Hills, Calif.

Application December 8, 1936, Serial No. 114,813

6 Claims. (Cl. 260—668)

This invention pertains generally to the manufacture from petroleum, of diluents, solvents, plasticizers, aromatic hydrocarbons, spray oils, Diesel oils, high grade petroleum distillates, etc.

5 The invention has to do particularly with processes for chemically converting mineral oils to produce aromatic hydrocarbons as well as base materials for the manufacture of dyes, chemicals, essential oils, resins, varnishes, etc. By "chemically converting" I mean the transforming of hydrocarbons to compounds of different chemical structure or formulae.

In the past, the production and derivation of aromatic hydrocarbons for such uses has for the 10 most part been confined to coal tar produced by the pyrolysis of coal in by-product coke ovens, and for practical and commercial reasons to the coal producing regions. As compared to my process, the cost of manufacturing aromatic hydrocarbons from coal tars is high, and the cost 15 is substantially increased by the cost of transportation to points distant from the sources of coal supply. Petroleum oils constitute another 20 source of aromatic hydrocarbons for industrial uses, and from a commercial standpoint they are highly advantageous as base materials because of 25 their lower cost on the basis of potential aromatics. The availability of and the wide distribution of oil production minimizes expensive 30 transportation.

From a theoretical standpoint, the desirability 35 of utilizing petroleum oils as a base material for the production of aromatic hydrocarbons has been realized, but no successful method has been proposed whereby it is possible to obtain from 40 petroleum oils, aromatic hydrocarbons in commercial quantities that are of a quality comparable with those derived from the coal tars and at costs sufficiently low to render such manufacture commercially feasible. Accordingly, my primary object is to provide a process whereby aromatic hydrocarbons can be produced at costs materially below the costs of producing aromatic hydrocarbons from coal tars or other sources.

45 Crude petroleum oils (such as California crude oil) contain paraffinic and napthenic hydrocarbons, and from a refining and commercial standpoint in most cases a percentage of tars or waxes which are objectionable. Petroleum oils such as 50 those produced from a so-called cracking process contain paraffinic, olefinic and napthenic hydrocarbons. The paraffinic hydrocarbons, when separated from the napthenic and olefinic hydrocarbons and fractionated to the proper boiling range, are desirable for use as Diesel oils, spray

oils, or any oil which requires a high concentration of paraffinic hydrocarbons. The paraffinic, olefinic and napthenic hydrocarbons have dissimilar chemical characteristics pertaining to their solubility in organic solvents such as liquid sulphur dioxide, furfural, acrolein, etc., the paraffinic being insoluble and the olefinic and napthenic being soluble.

5 In accordance with the invention I am able to convert into aromatic hydrocarbons the napthenic portion of any suitable petroleum distillate. This napthenic portion is that portion which is soluble in an organic solvent such as liquid sulphur dioxide, furfural, acrolein, etc. This distillate may be the vaporizable portion of any 10 suitable crude oil from which the tars, waxes, or heavy residuum has been removed. This distillate may have a boiling range from approximately 100° F. to 800° F. and it may consist of any suitable fraction, say one having a boiling 15 range of 100° F. more or less within these limits, if desirable.

20 I am able to convert into aromatic hydrocarbons the napthenic and olefinic portions of any suitable distillate produced from a so-called cracking plant. This napthenic and olefinic portion is that portion which is soluble in an organic solvent such as liquid sulphur dioxide, furfural, acrolein, etc. This distillate may be the vaporizable portion of the product produced from the 25 cracking plant and may have a boiling range from approximately 100° F. to 800° F. and it may consist of any suitable fraction say one having a boiling 30 range of 100° F. more or less within these limits if desirable.

35 In accordance with the invention, in the manufacture of aromatic hydrocarbons, diluents, solvents and plasticizers, the presence of paraffinic hydrocarbons is undesirable in that, being saturated, they do not respond to molecular rearrangement into aromatic hydrocarbons under 40 the conditions later described. However, in stating that the saturated paraffinic hydrocarbons are undesirable, it is to be understood they are undesirable only as charging stock for that part of my process involving more directly the conversion of the charging stock into aromatic hydrocarbons, diluents, solvents and plasticizers. These paraffinic hydrocarbons when separated from the napthenic and olefinic hydrocarbons by 45 use of a selective solvent such as herein mentioned, are highly desirable for use as Diesel oils, spray oils, high grade distillate or any petroleum product which requires a high concentration of 50 paraffinic hydrocarbons. The charging stock 55

may be a distillate produced from a crude oil or a distillate produced from a synthetic oil from a so-called cracking plant, or any fraction of suitable predetermined boiling range.

Starting with a petroleum oil distillate as charging stock, the distillate first is subjected to a solvent treatment in which the paraffinic hydrocarbons are separated from the naphthenic by reason of the selective solubility of the naphthenes in the solvent. Starting with a synthetic distillate or charging stock produced from a cracking plant, the synthetic distillate first is subjected to a solvent treatment in which the paraffin hydrocarbons are separated from the naphthenic and olefinic by reason of the selective solubility of the naphthenes and olefins in the solvent. After separating the paraffinic hydrocarbons from the small amount of solvent entrained therein I have stock suitable in accordance with the process for high grade spray oils, Diesel oils or any high grade oil requiring a large concentration of paraffinic hydrocarbons. In most cases it being only necessary to fractionate these paraffinic hydrocarbons to the proper boiling range and passing same to storage for sale. Then after separating the solvent from either or both the naphthenes and olefins, as the case may be, I have a stock suitable in accordance with the process for the production of aromatic hydrocarbons, diluents, solvents and plasticizers. The solvent may be recovered by the usual methods of distillation. The portion of the distillate or charging stock soluble in the solvent will be referred to as the "soluble oil." This soluble oil being either the soluble portion secured from the crude oil distillate or the soluble portion of the distillate secured from the cracking plant, or both.

Generally speaking, the invention involves subjecting the soluble oil to temperature and pressure conditions in combination with a low molecular weight gas under which the soluble oil undergoes molecular rearrangement into hydrocarbons that under proper conditions and control are aromatic in nature or at least possessed of the characteristic properties of aromatic hydrocarbons. In this respect the invention is distinguished from the mere cracking of a solvent extract as has heretofore been proposed for the purpose of obtaining lighter and more volatile fuels, from a relatively heavy oil obtained by a solvent treatment. Such processes as have been proposed may incidentally result in the production of some aromatics, but they are distinguished in that they are incapable of producing aromatic hydrocarbons alone or in commercial quantities from an economical standpoint. The known processes of vapor phase cracking in tubes have the disadvantage of producing excessive quantities of fixed gases, due to the extreme vapor temperatures (around 1500° F.) required. Also such vapor phase cracking processes require a high ratio of fuel-to-charging stock and high heating gas velocities across the tubes, which give large heat losses up the stack. These are all conditions which produce heavy coke deposits in the tubes, and shorten the life of the equipment, making the whole operation uneconomical for the production of aromatic hydrocarbons.

I have found that in order to bring about molecular rearrangement of the soluble oil into aromatic hydrocarbons, it is necessary to avoid excessive temperatures and to effect the molecular rearrangement of the soluble oil vapors under conditions of relatively low oil vapor pressure. In order to establish the conditions conducive to

the formation of aromatic hydrocarbons I subject the soluble oil vapors to a molecular rearrangement directly admixed with a suitable low molecular weight heated gas, the proportions of gas and vapors being such that in accordance with the laws of partial pressures, the actual or effective vapor pressure of the soluble oil vapors undergoing molecular rearrangement, is substantially reduced below the normal gauge pressure at the existent temperature. By directly admixing relatively high proportions of the heated low molecular weight gases with the soluble oil vapors in suitable equipment, I am able to produce aromatic hydrocarbons from petroleum without the characteristic difficulties that have been experienced in the past.

In the final steps of the process, the converted oil vapors are subjected to suitable fractional condensation to obtain products having boiling ranges suitable for the particular purposes for which the fractions are to be used.

The invention, and the complete process, will perhaps be more fully understood and explained to best advantage by reference to the accompanying flow sheet illustrating diagrammatically and conventionally the various stages of the process. It will be understood that any suitable apparatus may be employed for carrying out the invention, and that the drawing is to be regarded merely as illustrative of the invention in one of its typical and preferred embodiments.

Assuming the initial oil or charging stock to be processed, to consist of a California type crude oil containing both saturated and naphthenic hydrocarbons, the oil first may be topped in a skimming plant 10, the heavier ends being sent to storage through line 11, and suitable lighter fractions within the desired boiling range, after removal of tarry bodies, taken through line 12 to a suitable solvent extraction plant, diagrammatically indicated at 13. Where the crude oil has a high saturated hydrocarbon content and it is desired to convert the saturated compounds into unsaturated compounds suitable for conversion into aromatics, I may first subject the crude, before or after being topped, to cracking in a plant 14, running the residuum to storage through line 14a, and conducting the lighter fractions, consisting mainly of paraffins, naphthenes and olefins, after removal of tars, through line 15 for treatment in the solvent extraction plant 13.

As previously mentioned, the purpose of the solvent extraction plant 13 is to separate the naphthenic and olefinic (or either when only one type is present) constituents of the charging stock from the saturated hydrocarbons. Solvent extraction systems of this character are well known and require no detailed explanation or showing. It will suffice to state that any suitable process may be employed for accomplishing the extraction. Likewise, I may employ any suitable solvent, such as liquid sulphur dioxide, croton aldehyde, nitrobenzene, etc., petroleum oil fractions where oils of certain boiling range are being treated. The use of liquid sulphur dioxide under pressure and proper conditions of temperature however is preferred as a selective solvent. In the extraction plant 13, the naphthenic and olefinic hydrocarbons are dissolved in the sulphur dioxide, and thereby separated from the insoluble paraffinic hydrocarbons. The latter may be removed through line 16 for any desired further treatment and for such uses as Diesel, spray oils, or any other uses for which an oil is particularly

suiting by reason of its high content of paraffin series hydrocarbons.

The dissolved constituents of the solvent treated oil pass through line 17 to a solvent separating plant 18 in which the sulphur dioxide is distilled off for recovery through line 19, leaving the naphthenic and olefinic hydrocarbons in proper condition for conversion into aromatics. At this point it may be observed that the oil thus obtained by the solvent extraction process preferably will have an approximate boiling range within the limits of 100° F. to 800° F., and it may consist of any suitable fraction, say one having a boiling range of 100° F., more or less, within these limits. In general, the particular boiling range of the separated soluble oil will be selected in accordance with the type of final (aromatic) product being manufactured, and of course the type and characteristics of the oil treated in the solvent extraction plant will be predetermined accordingly. In most instances it is advisable to use as a charging stock for the conversion unit, fractions having relatively narrow boiling ranges since, by using such stocks, I reduce the amount of fixed gases produced, and secure a higher recovery of liquid products. The lower boiling charging stocks give higher percentages of lower boiling aromatic hydrocarbons in the finished products than are obtained when high boiling range charging stocks are used. Charging stocks of different boiling points may require slight variations in operating conditions, but these variations pertain to slight changes in temperature, time of reaction, pressure and volume of combustion gases, and do not alter the fundamentals of the process.

From the sulphur dioxide separation plant 18 the oil passes through line 20 to a vaporizing retort or pipe still 21 wherein the oil is heated to vaporizing temperature under a suitable pressure, for example 60 pounds gauge or over, or under, as may be determined by a back pressure valve 22 in the vapor discharge line 23. The vapors are discharged into an enlarged zone within the flash drum 24, with sufficient pressure drop at the valve 22 to facilitate vaporization of any unvolatilized oil. Any unvaporizable residue may be drained from the flash chamber through line 24a. For the purpose of insuring complete vaporization of the oil and to reduce coke formation in the superheater, I preferably inject superheated steam through line 25 into the flash drum, the steam commingling with the vapors and the mixture flowing through line 26 to a tubular superheater 27 in which the oil vapor and steam mixture is heated to a suitable temperature preferably within the range of 900° F. to 1150° F. The oil vapors, together with the admixed steam when used, are next combined by suitable means with a heated low molecular weight gas that may be generated by any suitable means, for example in a combustion chamber 28 within which fuel such as distillate or natural gas supplied via line 29 from a compressor or pressure container 30, is burned in the presence of an air stream being discharged by a compressor 31 through line 32 into the combustion chamber.

The fuel is burned with a relatively high proportion of air, for example in a ratio of 14 pounds of air to 1 pound of fuel, or in excess thereof. The combustion gases, consisting mainly of carbon monoxide, leave the combustion chamber under pressure through passage 33 and are mixed therein with the superheated oil vapors from line 34 leading from the superheater 27.

The temperature of the outlet combustion gases is controlled so that the temperature of the gas and oil vapor mixture ordinarily will be in the neighborhood of 1200° F., and preferably not substantially in excess of 1350° F. In the treatment of many oils, it has been found that a maximum conversion to aromatics requires a reaction chamber temperature not substantially below 1100° F. and this may be regarded as a preferred minimum conversion temperature. It may be that other oils will respond to lower temperatures, but as stated, a temperature of 1100° F. may be given as preferred. The gas and oil vapor mixture enters a suitable reaction chamber 35 containing an enlarged zone within which the oil vapors undergo molecular rearrangement into aromatic hydrocarbons at the temperatures stated, the rate of flow through the reaction chamber being regulated so that the vapors remain therein the length of time required for maximum conversion and reformation. Ordinarily the vapors will be held in the reaction chamber for a period approximating two minutes, which period however may vary in accordance with the characteristics of the charging stock and final product to be made.

Preferably the conversion will be caused to take place under a reaction chamber gauge pressure substantially above atmospheric pressure, the most suitable pressure in any instance being determinable in accordance with the nature of the charging stock and products desired. As illustrative, the reaction chamber pressure may vary within the range of from 15 to 100 pounds per sq. in. gauge. In order to obtain the desired partial pressure effect on the oil vapors by admixture with the low molecular weight gas, the proportion of gas in the mixture will greatly exceed the proportion of oil vapors and at any time the proportion of gas may be changed as it is desired to further reduce the partial pressure of the oil vapors to the lowest practical limit. As a general practice, I prefer to admix around 4 volumes of the combustion gas (inclusive or exclusive of steam, if present) with 1 volume of the oil vapors. In these proportions, the partial pressure of the combustion or uncondensable gas constituents of the mixture will substantially exceed the partial pressure of the oil vapors. However, as stated the gas-to-oil vapor ratio may be varied from this preferred ratio to obtain an oil vapor partial pressure most suitable for the desired results. Again, these proportions may be varied in accordance with the characteristics of the charging stock and the properties desired in the finished product. Tests have indicated that by maintaining the proper conditions, i. e., temperature, pressure and gas-to-oil vapor ratio in the reaction chamber, it is possible to obtain pure aromatic hydrocarbons.

Thus by controlling the volumes of combustion gases to volumes of superheated soluble oil vapors I am able to effect the molecular rearrangement of the soluble oil vapors at pressures considerably below the gauge pressure and am able to convert the superheated soluble oil vapors to aromatic hydrocarbons at temperature lower than thought possible heretofore. In other words the gauge pressure may show 40 pounds within the reaction chamber but due to the laws (Dalton's) of partial pressures the soluble oil vapors are undergoing molecular rearrangement at a much lower pressure than the recorded gauge pressure.

From the reaction chamber the oil vapors and combustion gases may be passed under pressure

through line 36 into a scrubbing tower 37, the purpose of which is to cool the reformed products to the extent necessary to retard polymerization and to prevent excessive formation of coke. The gas and vapors rising through the scrubber may be chilled or partially cooled by the use of a volatile reflux, as may be supplied through line 38 from the base of the fractionating column 39. Any condensate or heavy tars within the bottom of the scrubber may be drawn off through line 40. If desired a stripping action on the condensate in the scrubber may be had by injecting steam into the base through line 37a. After being cooled in the scrubber, the gas and vapor are discharged through line 41 to a fractionating apparatus, typically indicated generally at 42, and which may be of any suitable type capable of separating or fractionally condensing the aromatic vapors into the desired fractions or cuts. By means of a back pressure valve 43 in the vapor line 41, or at any other suitable location, the proper operating pressure may be maintained within the reaction chamber 35 and scrubber 37.

25 The fractionating column 39 may operate to fractionally condense and separate one or a series of the aromatic fractions, according to the desired boiling range of the product. For example, a heavier fraction may be taken from the base 30 of the column through line 44, and successively lighter fractions drawn off at intermediate points through outlets 45 and 46. Vapors leaving the fractionating column via line 47 are subjected to final condensation within condenser 48, the condensate, together with the uncondensed gases, thence flowing through line 49 into accumulator 50, from which the gases are exhausted through line 51 and the liquid product passed through line 52 to treaters or storage.

40 In a typical run, an initial charging stock consisting of a California distillate derived from a California crude oil having a gravity of 35.4 A. P. I., initial boiling point 420° F. and end point 572° F., was subjected to solvent extraction by 45 liquid sulphur dioxide, and after separation from the insoluble constituents of the crude distillate, the soluble oil showed the following boiling temperature and gravity properties by Hemple distillation:

50

Table I

Percent distilled over—	Tempera-ture	Gravity of oil	
		A. P. I.	Specific 60° F./60° F.
10	465	24.9	0.9047
20	478	21.7	0.9236
30	488	20.2	0.9328
40	494	19.2	0.9390
50	504	18.0	0.9465
60	508	17.1	0.9522
70	518	16.4	0.9587
80	524	15.6	0.9619
90	540	14.8	0.9672
97	568	13.4	0.9769

65 This oil, after vaporization with steam and being subjected to conversion by admixture with heated combustion gases as described in the foregoing, produced a total final liquid condensate yield of 76.2 parts (by weight based on the soluble extract), 16.4 parts of fixed gas and casing head gasoline, and 3.9 parts of carbon. In the following table the results of the Hemple distillation of the total (reformed) condensate are given:

Table II

Percent distilled over—	Tempera-ture, ° F.	Gravity of oil	
		A. P. I.	Specific 60° F./60° F.
10 (5% water)	210	32 (oil)	0.865
20 (2½% water)	300	25 (oil)	0.904
30	450	16.6	0.955
40	483	11.3	0.991
50	494	10.0	1.000
60	509	9.5	1.003
70	520	9.2	1.005
80	538	9.0	1.007
87.5	550	8.2	1.027

15 A comparison in the quality of fractions of this product with toluene made from coal tar pyrolysis is indicated by the following table showing the comparative results of such standard tests as determination of the dilution ratio, solubility in dimethyl sulphate, aniline cloud and kauri butanol values.

Table III

Boiling range, products from my process	Dilution ratio solution used $\frac{1}{2}$ second nitrocellulose cotton 10% by weight in butyl acetate	Solubility in dimethyl sulphate	Aniline cloud	Kauri butanol value
Up to 435° F.	3.1	100	-10C.	252
435° F. to 490° F.	3.3	100	-10C.	205
490° F. to 510° F.	3.2	100	-10C.	180
Commercial toluene	2.9	100	-10C.	145

25 From Table III it will be noted that the products of the present process are of high quality for uses as solvents with resins in the manufacture of varnishes and paints, as shown by the very high kauri butanol value; also that the products are highly suitable for the manufacture of lacquers, as shown by the high dilution ratio values. In these regards, among others, the product is superior to any of the usual diluents or solvents now being made from petroleum oils alone. It will be noted that the products are particularly suitable for use as paint thinners or carriers due to their high specific gravity and resultant ability to hold paint pigments in suspension. As further indications of the type of products capable of being produced by the invention, it may be observed that tests made by a refractometer (specific refractor dispersion method of Ward and Fulweiler, Industrial and Engineering Chemistry Analytical Edition of 1934, pages 396-400) indicate that the products are substantially 100% aromatic hydrocarbons and possess the qualities of those aromatics derived from the coal tars. The products are found to be completely soluble in three volumes of 98% sulphuric acid, and they are completely soluble in equal volumes of dimethyl sulphate.

30 In stating that the process is capable of producing products that according to the tests as described in the foregoing, are substantially entirely aromatic in nature, it is to be understood that the invention is not to be regarded as limited to the making of products 100% aromatic. I have found that superior diluents, solvents, plasticizers, etc., may be made that contain substantial or high percentages of aromatics, but which need not be entirely aromatic in their composition.

65

70

75

I claim:

1. A method of producing aromatic hydrocarbons and diluents and solvents of a predominantly aromatic hydrocarbon content whose dilution ratio, kauri butanol, and dimethyl sulfate values closely approach or equal those of coal tar aromatic hydrocarbons, produced by the pyrolysis of coal, which comprises treating a petroleum oil containing paraffinic and non paraffinic hydrocarbons with a selective solvent to remove the paraffinic hydrocarbons, recovering the non paraffinic soluble portion of the oil from the selective solvent by distillation, vaporizing and heating the non paraffinic portion of the oil, admixing and proportioning a heated gas of relatively low molecular weight with the heated oil vapors so that according to the laws of partial pressure the actual vapor pressure of the admixed oil vapors undergoing conversion is substantially reduced below the gauge pressure of the mixture, maintaining the mixture at a temperature and time of reaction causing chemical conversion of the oil vapors to substantially and predominantly aromatic hydrocarbons, and finally subjecting the converted oil vapors to fractionation, cooling, and condensation.
2. A method of producing aromatic hydrocarbons and diluents and solvents of a predominantly aromatic hydrocarbon content whose dilution ratio, kauri butanol, and dimethyl sulfate values closely approach or equal those of coal tar aromatic hydrocarbons, produced by the pyrolysis of coal, consisting in subjecting a petroleum oil to conditions of cracking to produce a cracked distillate, separating by distillation a desired fraction boiling within the limits from 100 degrees F. to 800 degrees F., contacting the desired fraction with a selective solvent to remove undesirable insoluble paraffinic hydrocarbons from said distillate, recovering the soluble portion of the distillate from the selective solvent by distillation, vaporizing and heating the soluble portion of the distillate, admixing and proportioning a heated gas of relatively low molecular weight

with the heated oil vapors so that according to the laws of partial pressure the actual vapor pressure of the admixed oil vapors undergoing conversion is substantially reduced below the gauge pressure of the mixture, maintaining the mixture at a temperature and time of reaction causing chemical conversion of the oil vapors to substantially and predominantly aromatic hydrocarbons, and finally subjecting the converted oil vapors to fractionation, cooling, and condensation.

3. A method of producing aromatic hydrocarbons and diluents and solvents of a predominantly aromatic hydrocarbon content whose dilution ratio, kauri butanol, and dimethyl sulfate values closely approach or equal those of coal tar aromatic hydrocarbons, produced by the pyrolysis of coal, which comprises heating and vaporizing a petroleum oil that has been solvent treated to remove undesirable paraffinic hydrocarbons, admixing and proportioning a heated gas of relatively low molecular weight with the heated oil vapors so that according to the laws of partial pressure the actual vapor pressure of the admixed oil vapors undergoing conversion is substantially reduced below the gauge pressure of the mixture, maintaining the mixture at a temperature and time of reaction causing chemical conversion of the oil vapors to substantially and predominantly aromatic hydrocarbons, and finally subjecting the converted oil vapors to fractionation, cooling, and condensation.

4. In a method such as that described in claim 1 wherein the selective solvent is SO_2 .

5. In a method such as that described in claim 1 wherein a narrow and low boiling fraction of a petroleum oil is treated to produce a high percentage yield of low boiling diluents, solvents and aromatic hydrocarbons.

6. In a method such as that described in claim 1 wherein a narrow and high boiling fraction of a petroleum oil is treated to produce a high percentage yield of high boiling diluents, solvents and aromatic hydrocarbons.

JAMES W. PUTT.
